[57] CLAIM

The ornamental design for a can holder, as shown and described.

DESCRIPTION

FIG. 1 is a top front isometric view of a can holder showing our new design;

FIG. 2 is a front elevational view thereof;

FIG. 3 is a side elevational view thereof, taken from one side;

FIG. 4 is a side elevational view thereof, taken from the one side, showing the can holder in a possible position of use;

FIG. 5 is a top plan view thereof; and

FIG. 6 is a bottom plan view thereof.

The view from the rear is identical to the view from the front; the view from the opposite side is identical to the view from the one side.

FIG.1

FIG.2

FIG.4

FIG.3

FIG.5

FIG.6
